Filed Aug. 19, 1957, Ser. No. 678,812

5 Claims. (Cl. 103—126)

This invention relates to a fluid pump and particularly to a pressure-loaded gear-type pump construction having novel means for lubricating relatively moving surfaces of the pump.

It is an important object of the present invention to provide a pump having novel means for diverting a controlled amount of fluid to relatively moving surfaces of the pump for efficiently and reliably lubricating said surfaces with a minimum loss of fluid from the working path of the pump.

A further object of the present invention is to provide a novel gear pump construction having means for providing a pulsating type of flow to relatively moving surfaces of the pump.

Another object of the present invention is to provide a bushing for a pressure-loaded gear pump having novel means for lubricating the bearing and lateral sealing surfaces thereof.

Still another object of the present invention is to provide a novel pump construction having a region about the periphery of the pump impeller between the inlet and outlet chambers of the pump where fluid pressure has a relatively large amplitude fluctuation during operation of the pump in combination with a lubricating passage communicating with said region of fluctuating pressure and with relatively moving surfaces of said pump.

Other objects, features and advantages of the present invention would be apparent from the following detailed description taken in connection with the accompanying drawings, in which:

Figure 1 is a longitudinal sectional view showing a gear-type fuel pump incorporating the features of the present invention;

Figure 2 is a side elevational view showing a bearing member constructed in accordance with the principles and teachings of the present invention;

Figure 3 is a longitudinal sectional view of the bearing member of Figure 2;

Figure 4 is a fragmentary longitudinal sectional view illustrating the cooperation between the bearing member of Figures 2 and 3 and the gear impelling means;

Figure 5 is a fragmentary end elevational view of a modified bearing member in accordance with the present invention; and

Figure 6 is a fragmentary longitudinal sectional view taken along the line VI—VI of Figure 5.

As shown on the drawings:

The principles and teachings of the present invention are particularly applicable to a gear type pump such as indicated generally by the reference numeral 10 in Figure 1. Such a pump comprises a casing 11 which has an end section 12 connected to the casing 11 by a plurality of fasteners 13. A cover member 14 is connected to the end section 12 by a plurality of fasteners 16. End section 17 provides a closure for the opposite end of casing 11 and has a fluid inlet 18 therein.

The casing 11, together with the end sections 12 and

17, forms a pump housing for the multiple pump 10 in which is contained a first centrifugal pumping stage indicated generally at 21 in series with a positive-displacement pumping stage consisting of two gear pump units indicated generally at 22 and 23, respectively. Each of the gear pump units 22 and 23 is similar in structural and functional characteristics. Fluid at the inlet 18 is initially pressurized by the centrifugal stage 21 and is supplied for further pressurization to the positive-displacement pumping stages 22 and 23 in parallel.

The cover member 14 is provided with the usual seal and bearing assembly indicated generally at 24 thereby to support a rotatable driving member indicated at 26 and including a splined shaft portion 27 adapted to be connected to a source of power supply, for example, the accessory drive of an aircraft jet engine if the pump 10 is employed as the fuel pump for the jet engine fuel system.

The driving member 26 extends inwardly of the pump housing and has a thrust flange 28 formed thereon concentrically surrounding a bore 29 which is partially splined as at 30 to couple with the complementary splines formed on the end of a first shaft member formed as a tubular quill shaft and indicated at 31.

25 The driving member 26 is further provided with a generally cylindrical collar 32, the walls of which surround a bore 33. The bore 33 has formed in the walls thereof a splined portion indicated at 34 which forms a coupling for the external splines formed on a shaft extension 36 on a driver gear 37 of the gear pump unit 23.

The collar 32 is provided with a first reduced shear neck 38 outwardly of the spline connection between the collar 32 and the shaft extension 36. By virtue of such provision, any abnormal force resulting from jamming or seizure of the gear pump unit 23 will effect torsional yielding of the reduced shear neck 38, thereby interrupting further operation of the gear pump unit 23.

The driver gear 37 is formed with a hollow bore 39 extending therethrough. Thus, the tubular quill shaft 31 extends inwardly through the bore 39 and has formed on the end thereof external splines 40 which mate with complementary internal splines formed in the bore 41 of a gear shaft extension 42 on the driver gear 43 of the gear pump unit 22.

45 The tubular quill shaft 31 is formed with a reduced shear neck 44 outwardly of the splined connection between the shaft 31 and the driver gear 43. Thus, if any abnormal force results from jamming or seizure of the gear pump unit 22, the shear neck 44 will yield torsionally to interrupt operation of the gear pump unit 22 without affecting or interrupting operation of the other pump components.

The end section 17 of the pump housing has a bore 55 formed therein in which is received a bearing sleeve 49 for journaling a shaft portion 50 provided on a gear 51. The gear 51 forms part of a speed proportioning means comprising a gear train rotatable in a gear chamber 52 formed in the end of the casing 11. The gear 51 is further steadied in its rotation by an axial bearing ring 53 supported by a radially inwardly extending strut 54 carried by the end section 17 of the pump housing.

A bore extends through the gear 51 and its shaft portion 50 and is provided with splines 56 mating with a 65 complementary plurality of external splines on the end of a second shaft member 57. The second shaft member 57 extends through the hollow bore 41 formed in the driver gear 43 of the gear pump unit 22 and extends into a bore 59 formed in the tubular shaft member 31. The shaft 31 is provided with internal splines and the shaft member 57 is provided with external splines as

shown at 60, thereby to couple the shaft members 31 and 57 for corotation.

The end section 17 of the pump housing is formed with a volute pumping chamber 61 in which is rotated a centrifugal impeller 62. The impeller 62 is keyed as at 63 and locked as at 64 to a shaft member 66 journaled in a plate-type insert 67 fastened in the end section 17 of the pump housing and providing both radial and axial bearing surfaces. At the end of the shaft member 66, there is provided a gear 68 meshing with the gear 51.

For greatest efficiency, the centrifugal impeller 62 should be rotated at higher speed than the gear pump units 22 and 23. Accordingly, the gear 51 is much larger in diameter than the gear 68, thereby permitting the gear train to function as a speed-proportioning means within the gear chamber 52 and thereby permitting the centrifugal impeller 62 to rotate in unison with the gear pump units 22 and 23 but at a much greater rotational speed.

The shaft member 57 is formed with a reduced shear neck 70 intermediate the spline connection of the shaft 57 with the shaft 31 and the spline connection of the shaft 57 with the gear 51. In this particular embodiment, it will be noted that the reduced shear neck 70 is located outwardly of the shear neck 44. By virtue of such provision, any abnormal force resulting from jamming or seizure of the centrifugal impeller 62 will cause the shear neck 70 to yield torsionally, thereby interrupting the further operation of the impeller 62 without interrupting the continued operation of the gear pump units 22 and 23.

It will be noted that each of the reduced shear necks including the shear neck 38, the shear neck 44 and the shear neck 70 is in register with the opening in the end of the pump closed by the cover member 14. Thus, separate parts can be conveniently replaced without requiring disassembly of the entire pump 10 since the broken parts can be conveniently removed from the pump merely by removing the cover member 14 at the end of the casing.

As shown in Figure 1 and in more detail in Figures 2 and 4, the gear pump units 22 and 23 may be provided with generally similar bushing members, and for convenience only the details of the gear pump unit 22 will be described herein. The construction of the gear pump unit 23 will be apparent from the following description of the gear pump unit 22.

As illustrated in Figure 1, gear pump unit 22 comprises a driver gear 43 having a series of peripherally spaced gear teeth such as 43a meshing with teeth 90a of a driven gear 90. The gears 43 and 90 are provided with integral shaft portions 42, 92, 93 and 94 journaled in bearing members or bushings 100, 101, 102 and 103. A retainer ring 107 is secured against a shoulder 11a of the casing 11 by a plurality of fasteners such as indicated at 109 to retain the pump unit 22 within its cavity in the casing 11. The casing 11 is provided with a central shoulder 11b against which are seated springs such as indicated at 111 for urging the bearing members 100 and 102 against one side of the gears 43 and 90. The space between the shoulder 11b and the opposing face of each of the bearing members 100 and 102 provides a pressure chamber 112 for receiving fluid at the discharge pressure of pump unit 22 to bias the movable bearing members 100 and 102 against the gears 43 and 90. Suitable sealing rings such as indicated at 114 and 115 may be provided for isolating the pressure chamber 112 associated with the movable bearing members 100 and 102 from adjacent spaces such as indicated at 120 which may be generally at the inlet pressure of the pump section 22, the space 120 being direct in fluid communication with the discharge side of centrifugal impeller 21.

The bearing members 100, 101, 102 and 103 are generally similar so that each member need not be described in detail herein. As seen in Figure 2, bearing member

103 comprises a generally tubular body portion 130 with a radially outwardly extending flange 131 at one end. The flange 131 has a front face 133 which forms a lateral sealing face engaging the adjoining side face of gear 90 as illustrated in Figure 4 to seal the fluid in the gear tooth spaces between gear teeth such as 90a. Flange 131 is provided with a chordal edge as indicated at 140 to complement the generally figure 8 shaped pumping cavity in which the gears rotate. Bearing member 101 associated with driver gear 43 has a mating chordal edge face 141, Figure 1, abutting the edge face 140 of flange 131.

The sealing face 133 of bearing member 103 is provided with an inlet relief recess 144 which provides an open region adjacent the tooth spaces on the inlet side of the pump to facilitate filling of the tooth spaces with fluid from the inlet chamber of the pump unit. The sealing face 133 is further provided with an outlet relief recess 146 as seen in Figure 2 which is located adjacent the tooth spaces on the outlet side of the pump to form a trapping relief and to improve the discharge characteristics of the pump.

The outer periphery of the sealing face 133 is indicated at 150 in Figure 2 and is concentric with the axis of the bearing member 103. For a portion of the outer periphery 150, there is provided a chamfered portion 152 forming a passage intercommunicating the tooth spaces at a portion of the periphery of the bearing member 103 with the relief recess 146 at the discharge side of the pump to tend to conduct fluid at discharge pressure to the tooth spaces which are registered with portion 152 at a given instant during rotation of gear 90.

At the radially innermost portion of the sealing surface 133, there is provided a chamfered relief 160 which operates to remove bearing load from bushing 103 adjacent the juncture of shaft portion 94 with gear 90. The bushing 103 has an axial bore 162 providing a bearing surface 130a for journaling shaft portion 94 of gear 90. Extending longitudinally of the bearing surface 130a is a groove 164 for distributing any fluid which may be at the relief portion 160 into the bearing area to assist in lubricating and cooling the bearing surface 130a.

Spaced longitudinally from the flange 131 on the bushing 103 is a second radially outwardly extending flange 166 having an outer peripheral surface 167 generally concentric to the axis of the bushing 103 and of contour corresponding to the periphery 150 of flange 131 for transmitting bearing support from the casing 11 to the bearing surface 130a.

In accordance with the principles and teachings of the present invention, means comprising a groove 180, Figures 2, 3 and 4, is provided for diverting a controlled amount of fluid from the working path of the pump. The working path of the pump may be considered to be the path taken by fluid which is transported by the tooth spaces, from a position in registry with inlet relief 144 to a position in registry with discharge relief 146. As the teeth such as indicated at 90a move along the working path from inlet relief 144 toward outlet relief 146 fluid pressure in the tooth spaces tends to progressively increase from inlet pressure to discharge pressure. With respect to a given region of the working path such as that communicating with groove 180, pressure pulsates between a relatively low pressure and a relatively higher pressure as the successive teeth 90a approach the groove 180 and then move past the groove. Preferably, the groove is of an extent to overlap the annular gear teeth engaging portion 133b of sealing face 133 and thus to communicate directly with the successive gear tooth spaces as they move past the groove. For this purpose, end 180a of the groove extends radially beyond the root diameter of gear 90 indicated at 90b in Figure 4. In the illustrated embodiment, the groove 180 at its radially inner end 180b extends into direct fluid communication with the recess provided by the chamfered portion 160 of the bearing member 103 to supply lubricating fluid to

the journal surface 130a via groove 164. The groove 180 will also tend to lubricate the bearing face 133 of the bearing member 103 at the annular gear hub engaging region thereof indicated at 133a radially inwardly of the root diameter of the gear 90. It is found that this construction provides proper lubrication for the lateral sealing face 133a and bearing surface 130a with much less loss of flow than a direct bleed to a constant high pressure.

By way of example of preferred dimensions of groove 180, in the illustrated embodiment the end 180a of the groove 180 may terminate .690 inch from the center line or axis of the bushing 103 and may have a depth of $\frac{1}{2}$ of an inch and a width of .016 inch. The root diameter of the gear 90 may be of the order of 1 and $1\frac{1}{32}$ inches, so that the overlap of the groove 180 with respect to the root diameter of gear 90 may be of the order of .02 inch. As seen in Figure 2, the groove 180 is preferably located substantially midway between the inlet relief recess 144 and the end of the chamfered portion 152 indicated at 152a nearest the inlet relief 144.

The bushing 101 indicated in Figure 1 is a mirror image of the bushing 103 in every respect and is provided with a groove corresponding to groove 180 in the corresponding position intermediate its inlet relief and a chamfer portion such as indicated at 152 for the bushing 103. Similarly, each of the movable bushings such as indicated at 102 in Figure 4 is provided with a chamfer portion such as indicated at 192 adjacent an internal journal surface 102a and is provided with a lubricating groove such as indicated at 194 positioned relative to the inlet relief and chamfer portion communicating with the discharge relief in the same manner as indicated for the groove 180 in Figure 2. The construction of the movable bearing members such as 102 will be apparent to those skilled in the art from Figures 1 and 4, but further details of such movable bearing members are disclosed in the Edwards et al. application U.S. Serial No. 636,772, filed January 28, 1957. The disclosure of this copending application is incorporated herein by reference with respect to its entire disclosure.

Figures 5 and 6 illustrate a modified form of lubricating groove which is designated by reference numeral 196. This groove 196 corresponds identically to the groove 180 in dimensions and position except for providing a straight axial end wall portion 197 at right angles to bottom portion 198 of groove 196 instead of the end portion 180a which has an end wall portion 180c which is curved radially inwardly and is not at right angles with respect to the bottom portion of groove 180 indicated at 199 in Figure 3. Other parts of the bushing of Figures 5 and 6 have been given the same reference numerals as in Figures 2 and 3 since the parts may be otherwise identical. It will be apparent that the groove 196 will function in a similar manner as described for the groove 180 so that further description of the function of the groove 196 is deemed unnecessary.

It will be apparent that many modifications and variations may be effected without departing from the scope of the novel concepts of the present invention.

We claim as our invention:

1. In combination, a pump having an inlet region and an outlet region and having gear-type impeller means for moving fluid along a working path from said inlet region to said outlet region during which the pressure of the fluid is progressively increased from an inlet pressure at said inlet region to an outlet pressure at said outlet region, said impeller means comprising a gear having a series of teeth defining spaces therebetween for receiving and transporting fluid along said working path and said spaces extending inwardly to the root diameter of said gear, the teeth moving progressively from the inlet region to the outlet region along the working path and then moving from the outlet region to the inlet region along a non-working path, shaft means for mounting said gear, a bearing member having an internal bore receiv-

ing said shaft means and having a lateral face engaging a side of said gear, said lateral face having means defining a passage communicating with said working path at a position intermediate said inlet and outlet regions and extending from a point slightly radially outwardly of the root diameter of said gear to a point communicating with the bore of said bearing member, said passage being substantially unobstructed to effectively communicate substantially the full pressure at said intermediate position of said working path to said bore of said bearing member, and being substantially isolated from said inlet region and said outlet region to provide a pressure intermediate inlet and outlet pressures.

2. In combination, a pump having inlet and outlet regions and having gear-type impeller means having a series of teeth defining fluid receiving spaces therebetween for moving fluid along a working path between said inlet and outlet regions during which the pressure of the fluid is progressively increased from an inlet pressure at the inlet region to an outlet pressure at the outlet region, the teeth then moving along a non-working path from the outlet region to the inlet region, shaft means for mounting said impeller means, bearing means having a lateral face engaging a side of said impeller means and having an internal bearing surface journaling said shaft means, said lateral face having a radially extending groove for communicating at one end with the spaces between successive teeth of the impeller means at said working path as the impeller means rotates and communicating at the other end with said internal bearing surface of said bearing means, and means comprising the disposition of said groove relative to said working path whereby a pulsating fluid pressure is generated at the end of said groove communicating with said spaces between successive teeth of the impeller means for supplying fluid to said internal bearing surface.

3. A bushing for a pressure-loaded gear pump comprising a generally annular member having an axial bore and having a lateral gear engaging face at one end thereof, said lateral gear engaging face having a radially inner annular portion for engaging a gear journalled thereby radially inwardly of the root diameter of the gear and a radially outer annular portion for engaging a gear journalled thereby radially outwardly of the root diameter of the gear, said member having inlet and outlet regions at spaced portions of the periphery thereof and having a peripheral passage extending from the outlet region toward the inlet region with one end thereof terminating in spaced relation to said inlet region to provide a portion of the periphery of the member where fluid is progressively pressurized from inlet pressure to outlet pressure, and said face having a groove therein extending radially intermediate said one end of said peripheral passage and said inlet region and said groove extending from a point approximately intermediate the radial extent of said lateral gear engaging face and in said radially outer annular portion thereof across said radially inner annular portion of said lateral gear engaging face to a point substantially directly communicating with the axial bore of said member for lubrication of said lateral face and said axial bore of said member.

4. A bushing for a pressure-loaded gear pump comprising a generally annular member having an axial bore and a lateral sealing face at one axial end thereof, said member having inlet and outlet relief regions adjacent the periphery thereof and having a longitudinal groove extending along the bore thereof and having a peripheral groove extending from the outlet relief region toward the inlet relief region terminating in spaced relation from the inlet relief region to provide a portion of the periphery of the member where fluid is progressively pressurized from inlet pressure to outlet pressure, and means defining a radial groove disposed at said portion of the periphery where fluid is pressurized and of radial extent to communicate at one end with pressurized fluid and

to communicate at the other end with the groove along said bore to supply lubricating fluid to said bore.

5. In combination, a pump having inlet and outlet regions and having rotatable impeller means with a series of peripherally spaced fluid receiving spaces for moving fluid along a working path from said inlet region to said outlet region, a bushing having a lateral face in engagement with one side of said impeller means for laterally sealing said fluid receiving spaces and having a peripheral passage for affording intercommunication between a series of said fluid receiving spaces instantaneously in registry therewith during rotation of said impeller means, said working path having a pressurizing region between said inlet region and the region thereof of communicating with said peripheral passage, said lateral face of said bushing having a straight groove extending generally radially and having one end terminating radially outwardly of the root diameter of said impeller means to communicate with each of the spaces of the impeller means in succession at said pressurizing region of said working path, said groove communicating with only one fluid receiving space at a time to provide a pulsating pressure from the successive spaces at said one end of said groove, said bushing having an axial bore for journaling said impeller means, and said groove terminating at its radially inner end in direct fluid com-

munication with said axial bore for supplying a pulsating lubricating pressure to said bore, and said groove being substantially isolated from said inlet region and said outlet region to provide a pressure amplitude at said groove intermediate the pressures at said inlet region and said outlet region.
